ATTACHMENT FOR SPINNING FRAMES

Jeter H. Riddle, Black Mountain, and Walter Garvis Reed, Swannanoa, N. C., assignors to Beacon Manufacturing Company, a corporation of Massachusetts

Application December 29, 1948, Serial No. 67,928

7 Claims. (Cl. 57—80)

1

This invention relates to spinning frames, and more particularly to an attachment for such frames adapted to avoid defective winding of bobbins formed on the frames.

It is common practice in processing yarn on a spinning frame to feed a reinforcing thread so that it is wound about the yarn to strengthen it. The yarn which is fed for reinforcing in this manner is usually referred to as filling, and the reinforcing thread is known as a reinforcing thread; the strengthened yarn being characterized by a spiral disposition of the reinforcing thread about the filling yarn. Strengthened yarn of this sort is used extensively, for example, in the manufacture of blankets and blanketeting.

One of the troublesome problems encountered in processing yarn in this manner is that the relatively weak filling yarn is subject to frequent breaking with the result that the stronger reinforcing thread remains trained along through the machine for winding onto the bobbins being built. As a single operator is commonly assigned to a number of frames, this situation can continue unattended for a considerable period with consequent defective winding of the bobbins and resulting seconds in subsequent weaving operations if the defective bobbins are not discovered.

Prior attempts have been made to avoid the above difficulty by providing a thread breaking means which will sever the reinforcing thread whenever the filling yarn breaks and thus prevent winding of the reinforcing thread alone onto the bobbins. These prior devices are somewhat complicated in their mechanical construction and have not been adopted generally. One of the features of our present invention is that it provides a very simple mechanism which is free of mechanical complications and is practically fool-proof in its operation. This device comprises a slotted member adapted for mounting on a spinning frame on which the filling yarn and reinforcing thread are combined by the usual twisting operation, and the slotted member being arranged adjacent to the travel of the twisted filling yarn and reinforcing thread such that they will not enter the slot in this member, but when the filling yarn breaks and the reinforcing thread is traveling alone, it will promptly enter the slot and be severed and thereby prevented from continuing to wind onto the bobbin without the filling yarn.

This slotted member may be either in the form of a fixed plate mounted on the frame guide bar at each twister location and having at least one

2

slot or notch formed therein and with sufficiently sharp edges to effect a shearing action on the reinforcing thread when it is entrapped in this slot; or the slots may be formed directly in the guide bar and this bar caused to reciprocate, engaging in sliding contact therewith a stationary member with which it forms a shearing action for severing or cutting of the reinforcing thread as the latter is brought into contact with the stationary member by the slotted reciprocating member.

As described herein and shown in the accompanying drawing, the thread breaking means is embodied in a twister frame which represents the principal field of application, though this invention may be adapted for use on other types of spinning frames.

Briefly described, one form of the thread breaking means of the present invention comprises a plate adapted for disposition at a suitable point in a spinning frame such as a twister frame in relation to the filling yarn and associated reinforcing thread, and formed with an edge having a configuration characterized by a plurality of slits extending into the body of the thread breaking plate transversely with respect to this edge and adapted to receive and grip the reinforcing thread and thereby sever it whenever the reinforcing thread is trained through the twister frame alone upon breaking of the filling yarn. Another important form of the thread breaking means of the present invention comprises an arrangement in which the guide bar of the twister frame is reciprocated and is formed for entrapping the reinforcing thread when it is trained through the twister frame alone upon breaking of the filling yarn, and in which stationary means formed for supporting the guide bar for reciprocation are disposed for shearing action with the reciprocating guide bar whereby the reinforcing thread is severed when entrapped.

The invention is described more in detail below in connection with the accompanying drawing, in which:

Fig. 1 is a fragmentary front elevation of a twister frame illustrating the operative disposition of the thread breaking plates on the guide bar;

Fig. 2 is a corresponding side elevation;

Fig. 3 is an enlarged front detail of this form of the thread breaking means;

Fig. 4 is a corresponding plan detail;

Fig. 5 is a perspective detail of the relative disposition of this form of the thread breaking

means and the filling yarn and associated reinforcing thread trained through the frame;

Fig. 6 is a corresponding perspective detail illustrating the operation of this form of the thread breaking means in severing the reinforcing thread when the filling yarn breaks;

Figs. 7 and 8 are respective front and bottom plan views illustrating an arrangement of this form of the thread breaking means disposed on the guide plate of the twister frame;

Fig. 9 is a fragmentary front elevation of a twister frame illustrating the operative disposition of the reciprocating guide bar form of the thread breaking means of the present invention;

Fig. 10 is a perspective detail of the relative disposition of the reciprocating guide bar form of the thread breaking means and the filling yarn and associated reinforcing thread trained through the frame; and,

Fig. 11 is a corresponding perspective detail illustrating the operation of the reciprocating guide bar form of the thread breaking means in severing the reinforcing thread when the filling yarn breaks.

Referring at first to Figs. 1 and 2 of the drawing, the disposition and arrangement of the thread breaking plates 10 of the present invention are shown in relation to a usual type of twister frame in which a yarn package 11 is disposed to supply filling yarn ends 12, and reinforcing threads 13 are trained for association with the filling yarn ends 12 from thread packages 14.

The filling yarn 12 is removed from the package 11 through a pair of drawing rolls 15, and is angled over a guide bar 16 to a twister head 17. Beyond the twister head 17, the filling yarn 12 is extended through a second pair of drawing rolls 18, and through a guide plate 19 to a ring and traveller mechanism 20 for winding onto the bobbins 21 being built.

The reinforcing threads 13 are taken off of the packages 14 over a guide rod 22 and are looped around a second guide rod 23 so as to be spiraled onto the filling yarn 12 by the action of the twister head 17 on the length of filling yarn extending from the first pair of drawing rolls 15. And the reinforcing threads 13 are carried forward in this manner with the filling yarn 12 to be built into the bobbins 21 being formed on the frame, as illustrated.

Now when the filling yarn 12 breaks, as frequently happens during normal operation of the twister frame, if the break occurs below the second pair of drawing rolls 18, the broken end will be taken up on the clearer roll 24; or if the break occurs above these rolls the filling yarn will accumulate at some other point on the machine as it is fed by the first pair of drawing rolls 15. In any event, the stronger reinforcing thread 13 will remain trained through the frame, as mentioned above, and will be wound onto the bobbins 21 alone as operation of the frame continues, unless this result is prevented.

It has been noted above that detection of this situation by an operator tending several frames may be delayed for a considerable period so that the possibility of winding defective bobbins is continually present. To remedy this difficulty, the thread breaking plate 10 of the present invention is disposed on the twister frame, appropriately in association with the guide bar 16 as shown in Figs. 1 and 2, to sever the reinforcing thread 13 whenever it is trained through the frame alone upon breaking of the filling yarn 12.

The form and arrangement of the thread breaking plate 10 is illustrated more in detail in Figs. 3 and 4 of the drawing. As shown, the thread breaking plate 10 comprises a relatively thin strip of metal, suitably a strip of spring steel or the like, formed for attachment to the guide bar 16 as by screws 25. As mentioned above, the filling yarn 12 and associated reinforcing thread 13 are angled over the guide bar 16 as they are lead to the twister head 17, and the thread breaking plate 10 is mounted on the guide bar 16 so that the plate 10 is spaced from the filling yarn 12 and associated reinforcing thread 13 when they are trained together through the machine.

When the filling yarn 12 breaks leaving the reinforcing thread 13 extended over the guide bar 16 alone, the disposition of the reinforcing thread 13 from the package 14 causes the reinforcing thread 13 to shift to the right on guide bar 16 (compare Fig. 1), and a slot 26 is formed in the top of guide bar 16 to receive the reinforcing thread 13 when it shifts in this manner. The slot 26 is angled slightly, as indicated in the drawing, to correspond with the angled disposition of the reinforcing thread 13 as it shifts. This slot 26 communicates with an aperture 27 in the body of guide bar 16, so that when the reinforcing thread 13 is received in slot 26 it is directed into the aperture 27 and accordingly comes into contact with the thread breaking plate 10.

The thread breaking plate 10 is arranged with a configurated edge disposed for contact by the reinforcing thread 13, the configuration of this edge being characterized by a plurality of slits 28 extending into the body of the thread breaking plate 10 and oriented transversely with respect to the edge. The slits 28 are preferably formed by shearing the thread breaking plate so that the portions defined by the slits are displaced with respect to each other and with respect to the body of the thread breaking plate 10, as illustrated in Figs. 3 and 4. This arrangement conditions the slits 28 with spaced edges at their open ends and a tapered throat, so that they are adapted to receive a reinforcing thread directed into contact with the edge of the thread breaking plate 10 and grip the reinforcing thread as it works into the tapered throat, and thus effect severing of the reinforcing thread.

This action of the thread breaking plate 10 is illustrated in Figs. 5 and 6 of the drawing. In Fig. 5 the disposition of the filling yarn 12 and associated reinforcing thread 13 when trained through the frame together is shown in relation to the thread breaking plate 10. Under these circumstances, the filling yarn 12 and reinforcing thread 13 are spaced from the thread breaking plate 10 by the guide bar 16, as noted above. Upon breaking of the filling yarn 12, however, the reinforcing thread 13 will shift as described above until it reaches the slot 26 and is thereby directed into the aperture 27 and into contact with the edge of the thread breaking plate 10. When this happens, the reinforcing thread 13 will find one of the slits 28 and enter it to be gripped and broken as illustrated in Fig. 6.

The action of the thread breaking plate 10 is thus automatic, and the particular bobbin 21 involved will continue to rotate without winding yarn until the operator tending the twister frame reaches this point and repairs the break in the filling yarn 12. As a result, defective winding of the bobbins 21 because of broken filling yarn is entirely avoided.

The above described arrangement of the thread

breaking plate 10 on the guide bar 16 has been found to be advantageous and convenient because the thread breaking plate 10 is easily installed at this point and is in full view so that breaks in the filling yarn are easily detected. It should be noted, however, that the thread breaking plate 10 may be mounted at any other suitable point on the twister frame, if desired. For example, a suitable alternative arrangement of the thread breaking plate 10 on the guide plate 19 is illustrated in Figs. 7 and 8 of the drawing. According to this arrangement, the thread breaking plate 10 is mounted on the bottom of the guide plate 19, as by screws 29, so that the edge configurated by the slits 28 is disposed for contact with a filling yarn and associated reinforcing thread extended through the guide plate. When the filling yarn and reinforcing thread are associated, the diameter of the resulting strand is too large to fit into any of the slits 28 and the strand will accordingly ride over the edge of the thread breaking plate 10. Upon breaking of the filling yarn, however, the remaining reinforcing thread will find one of the slits 28 and be received and gripped in this slit, and thereby severed, in the same manner as described above. The thread breaking plate 10 may likewise be disposed at any other suitable point in the twister frame system as may be convenient or necessary in particular circumstances.

The reciprocating guide bar form of the thread breaking means of the present invention is shown in Fig. 9 of the drawing. This form comprises an arrangement for reciprocating the guide bar 16 which is formed with a slot 30 for entrapping the reinforcing thread 13, as described further below. Studs 31, which are disposed for shearing action with the slotted portions of guide bar 16, are attached to the twister frame, as by lock nuts 32, for supporting the guide bar 16 for reciprocation. The studs 31 have heads 33 formed with grooves 34 for supporting the reciprocating guide bar 16 horizontally on the frame, and the edges of these grooves 34 cooperate with the edges of the slots 30 to effect the above mentioned shearing action. The guide bar 16 is reciprocated by a rocker arm 35, which is mounted on a rock shaft 36 actuated from a crank plate 37, or cam or the like, and connected to one end of the guide bar 16 by a pivoted connecting link member 38 which is arranged with a screw adjustment as at 39 for positioning the reciprocating traverse of the guide bar 16 with respect to the studs 31.

The form and arrangement of a stud 31 and a portion of the reciprocating guide bar 16 and their association on the frame before and after the filling yarn 12 breaks and the reinforcing thread 13 is severed are illustrated in detail in Figs. 10 and 11 of the drawing. The slot 30, like the slot 26 described above in another embodiment, is angled slightly, as indicated in the drawing, to correspond with the angled disposition of the reinforcing thread 13 as it shifts, as described further below.

As shown in Fig. 10, the filling yarn 12 and the associated reinforcing thread 13, when they are angled over the reciprocating guide bar 16, are positioned from the slot 30 and from the stud 31. The slot 30 is formed with a width smaller than the diameter of the filling yarn 12 and the associated reinforcing thread 13 so that only the reinforcing thread 13 will enter the slot 30 when trained through the frame alone. When the filling yarn 12 breaks leaving the reinforcing thread 13 extended over the reciprocating guide bar 16

alone, the disposition of the reinforcing thread 13 from the package 14 causes the reinforcing thread 13 to shift to the right on the guide bar 16, the shifting of the reinforcing thread 13 and the reciprocation of the guide bar 16 coacting to direct the reinforcing thread 13 into the angled slot 30. The guide bar 16 is reciprocated constantly during the operation of the twister frame by the crank plate actuated rocker arm 35 so that the reinforcing thread 13, after passing into the angled slot 30, is entrapped in the slot 30 and is directed by the horizontal movement of the guide bar 16 in the grooves 34 against the cooperating edges of the groove 34 and the edges of the slot 30, thereby severing the reinforcing thread 13 by a shearing action as shown in Fig. 11 of the drawing.

Like the action of the thread breaking plate 10, the action of the reciprocating guide bar form of the thread breaking means is automatic, and the particular bobbin 21 involved will continue to rotate without winding any material thereon until attended to by the operator. Thus, defective winding of the bobbins resulting from broken filling yarn is eliminated.

We claim:

1. In a spinning frame in which a filling yarn and reinforcing thread are twisted together, lead over a guide bar, and wound onto a bobbin, the improvement comprising a reciprocating slotted member over which the twisted filling yarn and reinforcing thread travel, the slot in said member having an insufficient width to accommodate the combined filling yarn and reinforcing thread, but having sufficient width to accommodate said reinforcing thread alone when the filling yarn breaks, and a fixed cooperating member with which said reciprocating member is associated in sliding contact and which will effect shearing of said reinforcing thread in said slot when the reciprocating member brings the reinforcing thread in contact with this fixed member.
2. A spinning frame as defined in claim 1 and in which said slotted reciprocating member is the guide bar on the spinning frame and is slotted adjacent to each individual twister location.
3. An attachment for spinning frames of the type in which a reinforcing thread is fed for association with filling yarn, comprising means formed for entrapping the reinforcing thread when said reinforcing thread is trained through the spinning frame alone upon breaking of said filling yarn, stationary means formed for supporting said entrapping means and disposed for shearing action with said entrapping means, and means for reciprocating said entrapping means for shearing action with said stationary means so that the reinforcing thread is severed when entrapped.
4. An attachment for spinning frames of the type in which a reinforcing thread is fed for association with filling yarn, comprising a reciprocating guide bar slotted for entrapping the reinforcing thread when said reinforcing thread is trained through the spinning frame alone upon breaking of said filling yarn, stationary means formed for supporting said guide bar and disposed for shearing action with the slotted portion of said guide bar, and means for reciprocating said guide bar for shearing action with said stationary means so that the reinforcing thread is severed when entrapped.
5. An attachment for spinning frames of the type in which a reinforcing thread is fed for association with filling yarn, comprising a recipro-

cating guide bar formed with a slot positioned to entrap the reinforcing thread when said reinforcing thread is trained through the spinning frame alone upon breaking of the filling yarn, a stud having a grooved head for supporting said guide bar horizontally on the frame, and means for reciprocating said guide bar so that the entrapped reinforcing thread is directed against the edges formed by the grooved head of the stud thereby severing the reinforcing thread by a shearing action.

6. In a spinning frame, the combination with means for feeding a plurality of reinforcing threads for association with strands of filling yarn and means for building the associated strands of filling yarn and reinforcing threads into bobbins, of thread breaking means for preventing defective winding of said bobbins, said thread breaking means comprising a guide bar mounted for reciprocation on said spinning frame and formed with slots positioned to entrap the reinforcing threads when said reinforcing threads are trained through the spinning frame alone upon breaking of said strands of filling yarn, stud members having grooved heads supporting said guide bar for reciprocation on the frame, means for reciprocating said guide bar, and means for positioning said guide bar with respect to said stud members whereby an entrapped reinforcing thread is severed by the shearing action of the grooved head of a stud member with the slotted portion of said guide bar.

7. In a spinning frame, the combination with

means for feeding a reinforcing thread for association with a filling yarn and means for building the associated filling yarn and reinforcing thread into bobbins, of thread breaking means comprising a guide bar mounted for reciprocation on said spinning frame and formed for entrapping the reinforcing thread when said reinforcing thread is trained through the spinning frame alone upon breaking of said filling yarn, stationary means supporting said guide bar for reciprocation on said spinning frame and disposed for shearing action with the entrapping portion of said guide bar, and means for reciprocating said guide bar for shearing action with said stationary means so that the reinforcing thread is severed when entrapped.
